US00D974808S

(12) **United States Design Patent** (10) **Patent No.:** **US D974,808 S**
Chen (45) **Date of Patent:** **** Jan. 10, 2023**

(54) **SWIVEL TO OPEN STANDING SHELF**

* cited by examiner

(71) Applicant: **Ximing Chen**, Shenzhen (CN)

Primary Examiner — Kelley A Donnelly

(72) Inventor: **Ximing Chen**, Shenzhen (CN)

(74) Attorney, Agent, or Firm — Nitin Kaushik

(73) Assignee: **Ximing Chen**, Shenzhen (CN)

CLAIM

(**) Term: **15 Years**

The ornamental design for a swivel to open standing shelf, as shown and described.

(21) Appl. No.: **29/834,360**

DESCRIPTION

(22) Filed: **Apr. 11, 2022**

FIG. 1 is a front, top and right-side perspective view of a first embodiment of a swivel to open standing shelf, showing my new design;

(51) **LOC (14) Cl.** **06-06**

FIG. 2 is a perspective view thereof shown in an open position;

(52) **U.S. Cl.**

USPC **D6/675.1**

(58) **Field of Classification Search**

FIG. 3 is a front view of FIG. 1;

USPC D6/672, 675, 675.1, 675.2, 679, 691,
D6/705, 705.6

FIG. 4 is a rear view of FIG. 1;

CPC A47B 46/00; A47B 46/005; A47B 47/021;
A47B 49/00; A47B 49/002; A47F 5/0081;
A47F 5/0087; A47F 5/0093

FIG. 5 is a left-side view of FIG. 1;

See application file for complete search history.

FIG. 6 is a right-side view of FIG. 1;

(56) **References Cited**

FIG. 7 is a top view of FIG. 1;

U.S. PATENT DOCUMENTS

FIG. 8 is a bottom view of FIG. 1;
